Primary Examiner — John A Voytek

(74) *Attorney, Agent, or Firm* — Lora J. Graentzdoerffer

(57) **CLAIM**

The ornamental design for a faucet, as shown and described.

DESCRIPTION

FIG. 1 is a perspective view of a faucet showing my design;

FIG. 2 is a front elevation view;

FIG. 3 is a rear elevation view;

FIG. 4 is a side elevation view;

FIG. 5 is a top plan view; and,

FIG. 6 is a bottom plan view.

The broken-line disclosures in the drawings represent portions of the faucet that form no part of the claimed design.

1 Claim, 6 Drawing Sheets
